UNITED STATES PATENT OFFICE.

GEORGE THOMPSON, OF MOUNT VERNON, NEW YORK, ASSIGNOR TO WESTERN ELECTRIC COMPANY, INCORPORATED, OF NEW YORK, N. Y., A CORPORATION OF NEW YORK.

DISTRIBUTING SWITCH.

Application filed September 4, 1919. Serial No. 321,651.

To all whom it may concern:

Be it known that I, GEORGE THOMPSON, a citizen of the United States, residing at Mount Vernon, in the county of Westchester, State of New York, have invented certain new and useful Improvements in Distributing Switches, of which the following is a full, clear, concise, and exact description.

10 This invention relates to automatic telephone exchange systems and more particularly to the mechanical construction of, and the arrangement of electrical circuits for, a switch suitable for use in such systems.

15 An object of this invention is to provide a switch which shall be simple in construction and rapid in operation.

The switch of the present invention is an improvement on that shown in Patent No. 20 1,375,762, issued April 26, 1921, and possesses all of the advantages of such switch with the additional advantage that the magnets which were used to mechanically withdraw the circuit closers from the path of 25 the operating elements are eliminated in the present invention.

20 The switch is provided with three movable contact operating members in fixed relation to one another. The switch is designed primarily for use as a hunting switch, and the peculiar angular relation between these three contact operating members and the sets of contacts arranged for cooperation with them is such that whichever contact operating member first reaches 30 a line in the desired electrical condition, will operate the contacts of such line. As a result of this arrangement, fewer steps are necessary before a line in the desired condition can be seized.

35 A switch of this type has a further advantage which is also due to the peculiar angular relation between the contact sets and the contact operating members. As a 40 result of this arrangement, the outgoing lines will not be tested in a predetermined order and, therefore, the apparatus associated with such outgoing lines will receive approximately equal shares of the work 50 which is to be distributed to them by the switch.

45 A features of the invention resides in the fact that a plurality of normal positions are provided for the switch and that the 55 switch will be advanced out of these nor-

mal positions between testing operations in accordance with the electrical condition of the incoming line.

The switch, as shown and described, is intended for use primarily as a distributing 60 switch individual to a calling subscriber's line. It is obvious, however, that a switch of this character is adapted to a variety of uses and the invention is, therefore, to be restricted only by the appended claims. 65

It is thought that the invention will be best understood from the following detailed description, reference being had to the accompanying drawings.

In the drawings, Fig. 1 shows operating 70 circuits for a switch embodying the features of the present invention, and Fig. 2 shows such portions of the switch mechanism as are necessary to an understanding of the 75 operation of the switch.

The mechanical construction of the switch will first be described. Referring now to Fig. 2, a shaft 1 is rotatably mounted on bearings of any suitable character. Secured to such shaft and rotatable therewith 80 is a yoke provided with arms 3, 4 and 5. The arms 3, 4 and 5 project radially from the center of rotation and are spaced apart equal angular distances. Since the three arms are spaced equally in the circumference of a circle, it is obvious that the angular distance between the arms is 120°. Fixedly secured to the shaft 1 is a ratchet wheel 6 which may be rotated in a clockwise direction under the control of a stepping pawl 7 mounted on the armature 8 of a stepping magnet 9. 85

90 Ten sets of contacts, similar to the sets indicated generally at 10, are spaced equally about the circumference of the circle. Ten sets of contacts similar to the sets indicated generally at 40 are also spaced equally about the circumference of the circle, the arrangement being such that contacts 40 appear one step in advance of each set 10. 95 Contacts 10 are arranged to be operated by the action of cams 11 and contacts 40 are arranged to be operated by cams 12, which cams are carried on each of the arms 3, 4 and 5, respectively. 100

105 Since the contact sets are placed equally about the circumference of the circle and are ten in number, it follows that the angular distances between adjacent contact sets is 36°. The ratchet wheel 6 is designed to 110

have sixty teeth so that the contact-operating members will be advanced 6° at each step of the ratchet wheel.

It will be assumed that the various points,

- 5 about the circumference of the circle described by the arms 3, 4 and 5 during rotation, at which contact sets 10 are located, are indicated by the letters A, B, C, D, E, F, G, H, M and N respectively. It will further
- 10 be assumed that at the time a call is initiated, the position of the various arms with respect to these contact sets is as shown in the drawings. By recalling that the contact sets are 36° apart, it will be obvious that if arm 3
- 15 must be advanced one step to operate the contacts at A, then the contact arm 4 will be one step in advance of position D and arm 5 will be three steps in advance of position G.
- 20 When the subscriber initiates a call, the arms 3, 4 and 5 will be advanced, due to the closure of a circuit completed through the contact set 40 which is in operated condition, due to the action of cam 12 on arm 3. The
- 25 switch is advanced one step whereupon the contacts 10 at position A are operated to complete a testing circuit. If the trunk associated with the contact set at A is busy, the switch is caused to make another step where-
- 30 upon cam 12 on arm 5 will operate contact set 40 at position H. Due to the calling condition of the line, the switch will be advanced another step to operate contact sets 10 at H and another test is made. Upon
- 35 completion of the conversation, the switch is advanced one step. Inspection of the drawing will show that whenever the switch is released, regardless of which arm and which contact set is utilized, there will always be
- 40 an arm within one step of a contact set 10, which means that an associated contact set 40 will be in an operated condition to cause the advance of the switch when the calling subscriber removes his receiver from the
- 45 switchhook.

Reverse movement and overthrow are prevented by the action of a holding pawl 13 which co-operates with the ratchet wheel 6.

The operating circuits of the switch will

- 50 now be described, reference being had to Fig. 1. When the subscriber whose substation is indicated at 14 removes his receiver from the switchhook, a circuit is completed from grounded battery, right-hand winding of differential stepping magnet 9, outer left-hand armature and back contact of cutoff relay 15, springs 16 and 17 of an operated set 40, conductor 18, through the calling substation, conductor 19, springs 20 and 21 of the
- 55 operated set 40, outermost right-hand armature and back contact of cut cutoff relay 15 to ground. Stepping magnet 9 is energized in this circuit and advances the switch one step, thus opening contact set 40 and closing contact set 10. If the trunk with which this
- 60 particular set 10 is associated is idle, there will be ground on contact 26. Circuits are then completed through both windings of differential magnet 9, thus preventing the energization of this magnet and causing the
- 65 switch to remain in this position. The circuit through the right-hand winding of magnet 9 at this time extends from grounded battery, right-hand winding of magnet 9, actuated springs 23 and 24, outermost right-hand armature and back contact of cutoff relay 15 to ground. The circuit through the left-hand winding of magnet 9 extends from grounded battery, left-hand winding of magnet 9, right-hand winding of cutoff relay 15, springs 25, 26, to ground at the armature and back contact of relay 28. As previously
- 70 stated, magnet 9 is not energized in this circuit, but cutoff relay 15 is energized and completes a locking circuit for itself extending from grounded battery, winding of relay 28, springs 31, 32, inner left-hand armature, front contact and left-hand winding of relay 15 to ground. Relay 28 is energized in this
- 75 circuit and removes the ground from the multiple test terminal 26 of the trunk to render the trunk busy to other hunting switches. Relay 15 at its inner and middle right-hand armatures extends the calling subscriber's line to the trunk by way of contacts 17 and 32, 20 and 33, 34 and 35, and 36 and 37.

- 85
- 90
- 95
- 100
- 105
- 110
- 115
- 120
- 125
- 130

In case the trunk had been busy, the above traced circuit through the left-hand winding of magnet 9 would have been open at the contact of relay 28. The circuit through the right-hand winding of magnet 9 would, therefore, have caused the switch to be advanced another step, at which time another set of contacts 40 would have been closed to advance the switch due to the closure of a circuit similar to the circuit previously described when the subscriber removed his receiver from the switchhook. In this way, the switch is caused to advance until an idle trunk is found.

When conversation is completed and the calling subscriber replaces his receiver, the circuit of relay 28 is broken at the first selector switch in any desired well-known manner. At the same time the circuit of cutoff relay 15 is broken and this relay de-energizes. Relay 28 is a slow-to-release relay and before its armature is retracted, a circuit is completed from grounded battery, right-hand winding of stepping magnet 9, closed contacts 23 and 24, outer right-hand armature and back contact of relay 15 to ground. This circuit is effective to energize the stepping magnet and cause the switch to advance one step, where it will remain until the calling subscriber again removes his receiver from the switchhook. When relay 28 fully retracts its armature, no circuit is completed for stepping magnet 9, since at this time the contact-operating

member 11 will have been advanced and springs 25 and 26 will be out of engagement with each other.

In case the line is seized as a called line 5 by a connector switch, battery supplied through the connector switch to test terminal 38 causes the energization of cutoff relay 15, thus removing the control of the stepping magnet 9 from the calling subscriber when he removes his receiver from 10 the switchhook to answer the call.

What is claimed is:

1. In an automatic switch, a plurality of fixed resilient contacts, a plurality of operating members in fixed relation to one another, means to establish electrical circuits through said contacts when engaged by said operating members by virtue of the resiliency of said contacts, a driving mechanism common to said members, and means to bring one of said members into operative relation with any one of said fixed resilient contacts, and means to bring each of the other operating members into operative relation with others of said contacts before said first member is brought into operative relation with another of said contacts.

2. In an automatic switch, a plurality of sets of fixed resilient contacts arranged in the arc of a circle, a plurality of rotatable members in fixed angular relation to one

another and in operative relation to said fixed contacts, means to complete electrical circuits through said fixed contacts when 35 operated by said members by virtue of the resiliency of said contacts, step-by-step mechanism to control the advance of said members, means to advance a given one of said members from one of said contact sets 40 to the next as a result of a plurality of steps by said step-by-step mechanism, means to bring said members successively into operative relation with any one of said fixed contact sets, and means to bring each of the 45 other operating members into operative relation with others of said contacts before said first member is brought into operative relation with another of said contacts.

3. In an automatic switch, a plurality of main circuit closers, a plurality of auxiliary circuit closers, means to alternately operate said main circuit closers and said auxiliary closers, said means including a plurality of operating members in fixed relation to one another, certain ones of said operating members being arranged to operate said main circuit closers and others of said operating members being arranged to operate said auxiliary circuit closers. 55 60

In witness whereof, I hereunto subscribe my name this 28th day of August, A. D., 1919.

GEORGE THOMPSON.
